DESIGN FOR A FLOWERPOT OR ANALOGOUS ARTICLE

Edwin P. Krehbiel, Hinsdale, Ill.

Application October 16, 1937, Serial No. 72,243

Term of patent 3½ years

To all whom it may concern:

Be it known that I, Edwin P. Krehbiel, a citizen of the United States, residing at 506 North Lincoln Street, Hinsdale, in the county of Du Page and State of Illinois, have invented a new, original, and ornamental Design for a Flowerpot or Analogous Article, of which the following is a specification, reference being had to the accompanying drawing forming part thereof.

Fig. 1 is a side elevation of a flowerpot embodying my new design;

Fig. 2 is a vertical section of same;

Fig. 3 is a half top plan view of same, and

Fig. 4 is a half bottom plan view of same.

I claim:

The ornamental design for a flowerpot or analogous article as shown.

EDWIN P. KREHBIEL.
